ABSTRACT OF THE DISCLOSURE

Detergent compositions for mechanically cleaning hard surfaces (e.g. dishes) are characterized by the presence therein of a mixture of metallic salt of citric acid (e.g. sodium citrate) and water soluble polymeric, organic polyelectrolyte (e.g. hydrolyzed maleic anhydride polymers). This mixture permits the reduction of or elimination of condensed phosphate salts commonly used in detergent compositions of this type (e.g. machine dishwashing detergents).

CROSS-REFERENCE TO RELATED APPLICATIONS

Ser. No. 836,597 filed June 25, 1969, now abandoned describes certain maleic anhydride polymers which are useful as polyelectrolytes in the practice of the present invention.

BACKGROUND OF THE INVENTION

Detergents for mechanically cleaning hard surfaces constitute a generally recognized class of detergent compositions. Machine dishwashing detergents constitute a subclass within this broad class that is of particular importance to the present invention. Machine dishwashing detergents must possess these characteristics without subcombination, is to emulsify and remove food soils, to inhibit the foam caused by certain food soils, to promote the wetting of dinnerware to thereby minimize or eliminate visually observable spotting, to remove stains such as those caused by coffee and tea, to prevent a buildup of soil and hard water films on dinner and glassware surfaces, to reduce or eliminate tarnishing of flatware, and to destroy bacteria. Additionally, machine dishwashing detergents must possess these characteristics without substantially etching or corroding or otherwise damaging the surfaces of dinnerware and flatware.

Machine dishwashing detergents are often highly alkaline (a pH above 10.0 and frequently above 12.0 at concentrations of 1 weight percent in water). Frequently, machine dishwashing detergents are formulated by mixing or otherwise combining alkaline condensed phosphate salts with other inorganic alkaline detergent salts or builders. Frequently, chlorine releasing agents and low foaming or defoaming organic surface active agents (e.g. non-ionic surfactants) are optionally and preferably included in such compositions.

In recent years, increasing attention has been focused upon environmental pollution problems (e.g. water pollution). Phosphates have been identified as a contributing factor to water pollution and considerable effort has been devoted to attempts at replacing all or at least some significant part of the condensed phosphate salts used in

2

detergents intended for cleaning hard surfaces (e.g. machine dishwashing detergents) with chemicals that are more ecologically acceptable. Of the numerous compounds that have been tested as substitutes for condensed phosphate salts (particularly as substitutes for sodium tripolyphosphate), very few chemicals have given promising results. Many chemicals lack the desired cleaning ability. Other chemicals lack the ability to sequester hard water metal ions beyond their stoichiometric presence (contrary to sodium tripolyphosphate which has such an ability). Still others create foam problems and still others are as much or more ecologically undesirable as the condensed phosphate salts.

Among the many chemicals tested for use as a substitute for sodium tripolyphosphate, nitrilo triacetic acid (or its salt) appears to be one of the most promising candidates. However, one disadvantageous effect of nitrilo triacetic acid (often called "NTA") is its tendency to de-stabilize chlorine in use solutions of such detergent compositions. Other disadvantages of NTA at the present time include cost, lack of general availability, and lack of threshold effect (i.e. inability to sequester hard water metal ions beyond its stoichiometric presence).

SUMMARY OF THE INVENTION

The present invention is based upon the discovery that mixtures of metallic salts of citric acid (e.g. sodium citrate) and water soluble polymeric organic polyelectrolytes are effective substitutes for condensed phosphate salts (e.g. for sodium tripolyphosphate) in detergent compositions intended for use in cleaning hard surfaces. The use of such mixtures in, for example, machine dishwashing detergents, produces dishwashing results that are commercially acceptable by today's industrial standards. The mixture is also effective at sequestering hard water metal ions beyond their stoichiometric presence (i.e. the combination exhibits the same threshold effect of alkaline condensed polyphosphates). Additionally, the mixture is stable toward chlorine releasing agents (e.g. potassium dichloroisocyanurate).

DETAILED DISCUSSION

Detergent compositions of the present invention can be formulated as either a solid detergent or as single or multiple package liquid detergent. These detergent compositions will be used, after appropriate dilution with water, for the mechanical or machine washing of hard surfaces (e.g. mechanical spray washing). They will find particular application as machine dishwashing detergents.

Solid or dry detergents can be formed by blending together the various detergent-forming ingredients to form a powder or granular product, or they can be agglomerated, pelletized or the like.

Multiple package liquid detergents are those machine wash-washing detergents which are formulated into two or more separate liquid components, each component being packaged separately. In the washing operation, the separate components are dispensed from their separate containers into the washing zone by suitable dispensing apparatus.

Although the present invention can be applied to or embodied in any of these various types of machine washing detergents, its greatest advantage is associated with the production of solid detergent compositions and single package liquid detergent compositions. Of these, the

formulation and use of solid machine dishwashing detergents is of particular significance.

The machine washing detergent compositions of the present invention will contain typical detergent forming ingredients plus the mixture of metallic salt of citric acid and water soluble polyelectrolyte.

The pH of these machine dishwashing detergents will normally be at least 10.0 at a concentration of 1 weight percent in water. pH's of from 12.0-12.5 are particularly desirable for many machine dishwashing uses. pH's in the 10-11 range are common for home use, while pH's above 12 are desired for industrial use.

The detergent compositions of the present invention are typically free of alkyl benzene sulfonates and, in use, produce little or no foam as contrasted to, for example, laundry detergents containing alkyl benzene sulfonates.

The citrates

Any of the water soluble metal salts of citric acid can be used in the practice of the present invention. However, all salts do not serve with equal effectiveness and the alkali metal salts are preferred. Sodium and potassium citrate are particularly preferred.

Commercial sodium citrate (more accurately described as trisodium citrate dihydrate) exists as white crystals or a granular powder. It is odorless, stable in air and has a slightly saline taste. Each molecule of trisodium citrate loses two molecules of water when heated to 150° C. Potassium citrate also exists as white crystals or powder. It is commercially available as the monohydrate (as contrasted to sodium citrate which exists as the dihydrate).

As used in the present invention, the amount of citrate employed will generally fall within the range of 5-60 weight percent on a dry formula basis. Water of hydration can be considered to be a part of the salt. More usually, the amount of citrate (whether hydrated or not) will be from 10-40 weight percent, e.g. 15-25 percent on the same basis.

If desired, mixtures of citrates can be used. Although it is not generally preferred, a citrate can be formed in situ from, for example, the combination of citric acid with sodium or potassium hydroxide. Citric acid is desirable when making liquid detergent compositions, but it quickly forms the corresponding salt since such liquid compositions are quite basic (i.e. pH above 10). The use of a pre-formed alkali metal citrate or a mixture thereof is generally preferred, particularly when making solid detergent compositions.

The weight ratio of citrate: polyelectrolyte will generally be above 1:1, frequently within the range of 2-10:1.

The polyelectrolytes

The polyelectrolytes useful in this invention are the water soluble organic polymeric polyelectrolytes. A wide variety of such polyelectrolytes are known as illustrated by the following U.S. patents:

3,308,067; Diehl; Mar. 7, 1967; 252/161
3,346,873; Herrmann; Oct. 10, 1967; 252/137
3,346,504; Herrmann; Oct. 10, 1967; 252/137

See also these U.S. patents:

3,463,730; Booth et al.; Aug. 26, 1967; 210/58
2,783,200; Crum et al.; Feb. 26, 1957; 210/23

All water soluble polyelectrolytes do not serve with equal effectiveness in any given dishwashing detergent formulation and it is desirable that the choice of type of polymer, molecular weight, and concentration be optimized for any given detergent formulation.

Suitable polyelectrolytes are the water soluble organic polymers of polycarboxylic acids (e.g. maleic acid) or of esters of ethylenically unsaturated carboxylic acids (e.g. butyl acrylate).

Water soluble carboxyl containing polyelectrolytes having an equivalent weight (calculated on an acid basis)

of about 58 to 150, more usually from about 58 to 110 are preferred. One particularly useful class of polyelectrolytes consists of: (a) homopolymers of maleic anhydride; and (b) low molecular weight linear copolymers of maleic anhydride and copolymerizable ethylenically unsaturated organic compounds such as ethylene, propylene, butylene, vinyl acetate, acrylonitrile, acrylic acid, methyl acrylate, ethyl acrylate, methyl vinyl ether, sodium vinyl sulfonate, styrene and the like. Structurally, these copolymers can be represented as follows.

wherein

R and R₁ can each be hydrogen or an organic radical containing from 1 to 8 carbon atoms (R and R₁ can be the same or different), Z is an organic radical containing 1 to 8 carbon atoms (note that Z is absent in the homopolymers), M is hydrogen, ammonium or an alkali metal (e.g. sodium), n is an integer, and x and y are terminal groups and are hydrogen or short chain organic groups.

In general, the copolymers are preferred.

It is somewhat difficult to establish an absolute value for an upper limit of the degree of polymerization (i.e. "n") above which the polyelectrolyte no longer functions as an efficient detergent builder. The fact is that practical considerations appear to be the primary determining factor as the degree of polymerization increases. For instance, as the molecular weight of a polymeric material increases, it is generally acknowledged that its water solubility decreases. It is essential to the present invention that the polyelectrolyte be adequately soluble in water under regular usage conditions. Recommended concentrations of polyelectrolytes generally range from about 0.005% to about 0.25% by weight (e.g. 0.01 to 0.12% by weight) of the washing solution. The upper operable limit, therefore, so far as the degree of polymerization is concerned is reached when it is no longer possible to get enough of the polyelectrolyte into solution or, in the case of liquid detergents, no longer possible to get enough polyelectrolyte into the liquid detergent concentrate.

For the purposes of this invention, the specific viscosity of the polyelectrolyte is preferably relatively low. Since there are viscosity differences inherently associated with different polymers, the preferred specific viscosities will vary. The polymer that is selected should be susceptible to handling and blending with the other components of the new detergent, as well as affording satisfactory performance. For example, when using a copolymer of ethylene and maleic anhydride it is preferred that the specific viscosity be not substantially in excess of a value of 2 as determined on a one weight percent solution of the copolymer in dimethyl formamide at 25° C. Similarly, with a vinyl acetate-maleic anhydride copolymer, it is preferred that the specific viscosity range be from 1.0 to 10.0 when determined on a four percent aqueous solution at 25° C.

Copolymerization of the maleic anhydride with unsaturated organic materials is known in the art. For example, U.S. Pat. No. 2,938,016 describes the production of low molecular weight olefin/maleic anhydride polymers useful in the practice of this invention.

Since all polyelectrolytes do not serve with equal effectiveness, it is useful to screen or select a polyelectrolyte on the basis of its apparent chelation value (ACV) as measured in milligrams of CaCO₃ sequestered per gram of polyelectrolyte. Below 200, the polyelectrolytes are gener-

ally ineffective for purposes of this invention.¹ Desirably, the ACV will be above 350, preferably above 500.

Apparent chelation values (ACV) for polyelectrolytes can be determined as follows. Dissolve a 0.5 to 1.0 gram sample in about 85 ml. of water, adjusting the pH to desired use value with NaOH or NH₄OH, add 10 ml. of 2% Na₂CO₃, then readjust the pH and make up the volume to 100 ml. with water. The solution is then titrated with a standard calcium acetate solution (0.25 M) using a magnetic stirrer. The titration is carried out in a semi-darkened room using a microscope spotlight until the first faint but permanent turbidity is obtained. The endpoint is not always completely sharply defined. Variations of $\pm 15\%$ from the average are not uncommon. Consequently, average values are more meaningful than single values (e.g. the average of three or more tests). The use of a spotlight and observation of Tyndall effect facilitates the determination of the end point. The final pH after the titration should be rechecked as the addition of a large amount of titrating solution may cause a drift in pH. It is possible to get two different endpoints for the ACV depending on which side of the equilibrium one approaches the endpoint, i.e. according to the equation:

In obtaining the data reported herein, the equilibrium was approached from direction 1 titration. It is possible to approach the equilibrium from direction 2 by agitating fine, solid CaCO₃ with chelate solutions.

Some typical results are shown in Table I which follows.

TABLE I.—APPARENT CHELATION VALUES FOR POLYELECTROLYTES

Polyelectrolyte	Initial pH	ACV mg. CaCO ₃ / grams
1. Sulfonated polyacrylic acid ¹	11.0	750
	12.0	750
2. Polyacrylamide ²	11.0	750
	10.0	700
	9.0	600
3. Ethylene/maleic copolymer (specific viscosity 0.6)	10.0	620
	11.0	770
	12.0	765
4. Ethylene/maleic copolymer (specific viscosity 1.0)	10.0	800
	11.0	580
	12.0	600
5. Vinyl acetate/maleic copolymer	10.0	800
	11.0	900
	12.0	700

¹ A sulfonated polyacrylic acid commercially available in the U.S.A. under the trademark "Calinox 214".

² A hydrolyzed polyacrylamide sold by American Cyanamid Co. under the trademark "Cyanamer P-35".

Detergent salts

In addition to the mixture of polyelectrolyte and citrate, the machine washing detergents of this invention will contain detergent salts, usually alkaline detergent salts.

Although most alkali metal condensed phosphate salts are alkaline and are often used in detergent compositions in large amounts, such condensed phosphate salts (e.g. sodium tripolyphosphate) can be employed in the compositions of this invention in reduced amounts (e.g., less than 10% by weight on a dry basis, preferably less than 5 weight percent on the same basis) or they can be eliminated entirely, in which case the desired level of alkalinity will be provided by the use of bases and/or non-phosphate alkaline salts such as carbonates, bicarbonates, silicates, borates, perborates and the like. Representative detergent salts are sodium carbonate, sodium bicarbonate, sodium hydroxide, sodium metasilicate, sodium borate, sodium perborate, di- and tri-sodium orthophosphates, sodium sesquicarbonate, potassium carbonate, sodium sesquisilicate, sodium orthosilicate, potassium bicarbonate, potassium silicates, potassium hydroxide, alkaline con-

densed phosphate salts (i.e. polyphosphates) such as tetrasodium pyrophosphate, tetrapotassium pyrophosphate and sodium tripolyphosphate, and glassy water soluble polyphosphates as known in the art.

Chlorine releasing agents

Chlorine releasing agents are usually and preferably included in the detergent compositions of the present invention.

Among the various chlorine releasing agents are chlorinated trisodium phosphate, polychloroisocyanuric acids and their salts or double salts, tri-chloromelamine, chloramine T, alkali metal and alkaline earth metal hypochlorites (e.g. sodium hypochlorite), mono, di, and tri-chloroisocyanuric acid, dichlorodimethyl hydantoin, solid chlorinated caustic soda, succinchlorimide, and the like.

Other ingredients or additives which can be included in the machine washing detergent compositions of the present invention include low foaming or non-foaming nonionic surfactants such as various polyoxyalkylene polymers, bases such as sodium and potassium hydroxide, fillers, corrosion inhibitors, coloring agents, and the like.

The present invention is further illustrated by the following specific examples. Unless otherwise indicated, all parts and percentages are by weight.

EXAMPLE 1

A machine dishwashing detergent was prepared from the following ingredients in the amounts indicated:

TABLE II

Ingredient:	Amount (percent)
Polyelectrolyte (see note 2, Table I)	3.0
Commercial sodium citrate	15.0
Soda ash, spray dried	59.0
Liquid sodium silicate (RU)	20.0
Chlorine bleach (sodium dichloroisocyanurate)	1.0
Defoaming non-ionic surfactant ¹	2.0

¹ A polyoxyalkylene product available in the U.S.A. under the trademark "DO-97," a product of Economics Laboratory, Inc.

This product, which is a dry granular product, was made by adding the surfactant to the soda ash to thereby absorb the surfactant, and then adding the silicate to the mixture with agitation to encapsulate the prior mixture and form a dry granular product. Thereafter, the remaining ingredients were added with agitation. This product has a pH (1% concentration) above 11.0.

When tested in a home dishwasher, this product gave very satisfactory performance when compared to a commercially available machine dishwashing detergent containing sodium tripolyphosphate (but not containing a polyelectrolyte or citrate).

EXAMPLE 2

A liquid machine washing concentrate having a pH above 12 was prepared from the following ingredients in the amounts indicated:

TABLE III

Ingredient:	Amount (percent)
Citric acid, anhydrous	10.0
KOH (45%)	50.0
Polyelectrolyte ¹	5.0
Sodium hypochlorite (12.5%)	15.0
Water, soft	20.0

¹ A 50% active aqueous slurry of a vinyl acetate/maleic anhydride copolymer (sodium salt) made according to the procedure of Serial No. 836,597, previously cited (mole ratio of vinyl acetate to maleic anhydride of 1:1; see Table I, polyelectrolyte number 5 (RO-46, a polymer made by Economics Laboratory, Inc.)).

The concentrate was formed by dissolving the citric acid in water, then adding the KOH, and finally adding the polyelectrolyte (all with agitation). The resulting mix-

¹ Some polyelectrolytes having an ACV below 200 are effective (e.g. certain styrene/maleic anhydride copolymers and carboxy methyl cellulose).

ture (which had become hot) was cooled below 90° F. and then the sodium hypochlorite was added.

EXAMPLE 3

A liquid machine dishwashing concentrate (less expensive than Example 2) was prepared from the following ingredients by the procedure of Example 2.

TABLE IV

Ingredient:	Amount (percent)
Citric acid, anhydrous	8.0
Sodium hydroxide (50%)	35.0
Polyelectrolyte ¹	8.0
Sodium hypochlorite (100%) ²	1.5
Water, soft	47.5

¹ The vinyl acetate maleic anhydride copolymer of Example 2.

² This can be provided in several ways, e.g. by using dilute aqueous solutions.

EXAMPLE 4

A powdered machine dishwashing detergent was prepared from the following ingredients in the amounts indicated:

TABLE V

Ingredient:	Amount (percent)
Sodium citrate, dihydrate	10.0
Polyelectrolyte ¹ (50%)	5.0
Light ash (i.e. sodium carbonate)	80.0
Sodium tripolyphosphate	3.0
Chlorine dry bleach ²	1.0
Organic defoamer ³	1.0

¹ See footnote 1 to Table IV.

² Sodium dichloroisocyanurate.

³ A polyoxyalkylene known as "DO-97," a product of Economics Laboratory, Inc., U.S.A.

The product is made by pouring the polyelectrolyte (a 50% active aqueous slurry) and the organic defoamer onto the ash with mixing until a dry product is obtained. The remaining ingredients can be admixed with the powder in any order.

What is claimed is:

1. Detergent compositions suitable for machine dishwashing and consisting essentially of:
  - (a) alkaline detergent salt which may include not more than 10% alkali metal polyphosphates;
  - (b) from 5 to 60% alkali metal salt of citric acid; and
  - (c) water soluble polymeric organic polyelectrolyte in a weight ratio of citrate to polyelectrolyte of at least about 1:1, said polyelectrolyte being selected from the group consisting of maleic anhydride/vinyl acetate copolymer, polyacrylamide, ethylene/maleic copolymer and sulfonated polyacrylic acid.
2. Improved detergents of claim 1 in which the polyelectrolyte is a maleic/vinyl acetate copolymer.
3. Detergents of claim 1 which are solid machine dishwashing detergents, wherein said salt of citric acid is sodium citrate and wherein said detergent contains, in addition to the listed ingredients, a chlorine releasing agent selected from the group consisting of polychloroisocyanuric acids and their salts.
4. Detergents of claim 1 wherein said detergent is a liquid concentrate for machine dishwashing, is free of alkali metal polyphosphate and, in addition to the listed ingredients, contains a chlorine releasing agent.

5. Improved detergents of claim 1 which are solid detergents, wherein the polyelectrolyte has an apparent chelation value of at least 350, and wherein the weight ratio of citrate to polyelectrolyte is between about 2:1 and 10:1.

6. Detergents of claim 2 which are solid machine dishwashing detergents, which have a pH at a 1% concentration in water of at least 10.0, and which contain less than 5% by weight of alkali metal polyphosphate.

7. Solid detergent compositions suitable for the machine cleaning of dishes and consisting essentially of:

(a) water soluble polymeric organic polyelectrolyte having an equivalent weight of about 58-110 and an apparent chelation value above 500; said polyelectrolyte being selected from the group consisting of maleic anhydride/vinyl acetate copolymer, polyacrylamide, ethylene/maleic copolymer and sulfonated polyacrylic acid;

(b) from 10-40% by weight of sodium or potassium salt of citric acid, the weight ratio of said salt to said polyelectrolyte being at least 1:1 and not more than about 5:1;

(c) alkaline detergent salt which may include not more than 10% by weight of alkali metal polyphosphate; and

(d) chlorine releasing agent selected from the group consisting of polychloroisocyanuric acids and their salts;

said compositions being free of alkyl benzene sulfonates.

8. Detergents of claim 7 wherein:

(a) said citric acid salt is sodium citrate;

(b) said detergent salt includes soda ash;

(c) said chlorine releasing agent is sodium dichloroisocyanurate;

(d) said detergent includes a defoaming polyoxyalkylene polymer; and

(e) said composition is free of alkali metal polyphosphates.

9. Liquid detergent compositions which consist essentially of:

(a) about 8% by weight of anhydrous citric acid;

(b) about 8% by weight of a 50% aqueous slurry of a vinyl acetate/maleic anhydride copolymer (mole ratio of 1:1) having an apparent chelation value above 500;

(c) about 35% of a 50% aqueous solution of sodium hydroxide;

(d) about 1.5% of sodium hypochlorite; and

(e) the balance to 100% of water.
